ATTORNEY

UNITED STATES PATENT OFFICE.

WILLIAM WEISS, OF PHILADELPHIA, PENNSYLVANIA.

GARMENT-POCKET.

1,316,526.

Specification of Letters Patent. Patented Sept. 16, 1919.

Application filed September 5, 1917. Serial No. 189,853.

To all whom it may concern:

Be it known that I, WILLIAM WEISS is a citizen of the United States, residing at 4833 Walnut St., Philadelphia, in the county 5 of Philadelphia and State of Pennsylvania, have invented new and useful Improvements in Garment-Pockets, of which the following is a specification.

This invention relates to garments, and 10 more particularly to pockets for apparel, and has for an object to provide a pocket which when the garment is in use, will not bulge outwardly, and in which the edge of the pocket adjacent the opening thereto, 15 will at all times lie flat against the body of the garment.

My invention comprehends, among other things, a pocket which is so formed that the face or outer side of the pocket will at all 20 times lie flat and not bulge from the side of the garment, even though the contents of the pocket may be of a nature which ordinarily bulges the general forms of pockets now applied to garments. More particularly, the invention comprehends what is 25 known as a patch pocket; namely, a pocket which is formed separately on a garment with an outer face sewed to the garment, and an inner part attached to the inner face of the 30 garment, with an opening in the garment so as to form the complete pocket, the outline of which will appear on the face of the garment. I am aware that various forms of pockets have been used heretofore, and 35 that several forms of pockets have been made with the idea of preventing bulging of the face of the pocket, but I find that these pockets do not accurately perform the objects for which they are designed and 40 are unpractical in that they are expensive to make, involve too many parts, and in view of various plaitings are hard to press properly, and cause bulging and wrinkling of the pocket more so even than the ordinary 45 pockets now in general use on garments.

My invention comprehends a very simple arrangement wherein the garment body is formed with an opening to the face of which a piece is applied, forming the outer side of 50 the pocket, with a second piece applied to the inner part of the garment to form the inner face and body of the pocket, said second piece being constructed with a bellows part at the bottom, so that when an article 55 is placed in the pocket, the pocket will bulge inwardly rather than outwardly, and that

the face of the pocket will be maintained in a plane substantially parallel to the plane of the garment body at all times.

In the further disclosure of the invention 60 reference is to be had to the following description and to the accompanying drawing, constituting a part of this specification, and in which—

Figure 1 is an elevation of the pocket 65 showing the face thereof.

Fig. 2 is a rear elevation of the pocket showing the inner side.

Fig. 3 is a vertical sectional view taken on the line 3—3 of Fig. 1, showing the 70 appearance of the pocket when an article is arranged therein.

Fig. 4 is a similar view showing the appearance of the pocket when there is no article therein, and

Fig. 5 is a horizontal sectional view taken through the pocket on the line 5—5 of 75 Fig. 1.

Referring more particularly to the views, the numeral 10 indicates the garment body 80 or material from which the entire garment, such as a coat, is made, and 11 the pocket, which as stated heretofore is in the nature of what is known to the trade as a patch pocket. Referring to Figs. 2 and 4 it will 85 be seen that the garment 10 has an opening 12 cut out, somewhat in configuration of what the pocket would appear to be later on, and attached by suitable stitching 13 to the face of the garment 10 is an outer 90 side 14 forming the outer face of the pocket. The pocket body is formed by having the flap 15, provided by cutting the garment proper to form the opening 12, hanging down immediately behind the front or face 95 14, with a bellows 16 sewed to the flap 15, as shown in Figs. 2 and 5, and to the inner face of the garment, the same stitching 13 for attaching the outer face 14 being also employed to sew the inner edge of the bellows 100 16 to the body of the garment, as shown in Fig. 5. The bellows 16 are somewhat biased, in that they become wider in width at the lower end of the pocket, as will be seen by referring to Figs. 3 and 4, and it will be 105 clearly seen that at the point where the outer edge of the bellows 16 connects with the flap 15, there is formed a seam 17, with a similar seam 18 formed where the inner edge of the bellows is sewed to the body of 110 the garment, the bellows, however, being so constructed that the seam 17 will lie with-

in the seam 18 and substantially adjacent thereto, to lie flush with the latter, when the pocket is devoid of any contents so that the pocket body will lie flat with respect to the front or outer face of the garment proper.

When an article 19 is placed in the pocket, it will be seen that whereas the pocket body in Fig. 4 normally lies in substantially the 10 plane of the garment body, said pocket will bulge but will not bulge outwardly to destroy the plane surface of the outer face of the pocket, but will bulge inwardly toward the body on account of the bellows construction provided, so that the coat or other article having a pocket of this character will not present a wrinkled appearance at or adjacent to the pocket when viewed from the exterior, but will present a neat and attractive 15 appearance, because the front or outer face of the pocket will be devoid of any bulging whatsoever.

From the foregoing description it will be seen that my pocket consists substantially of 20 two parts, one of which, namely, the back or inner face of the pocket is a part of the original garment material and integral therewith; whereas, the other or outer face of the pocket is of the same material and 25 sewed to the body of the garment, the inner part, or flap, having merely a bellows attached thereto and to the garment proper so as to form the desired inwardly bulging pocket, and preventing the outer face from 30 becoming wrinkled.

Still further with this construction, it will be seen that the upper edge of the pocket, namely, the horizontal edge 20, adjacent the entrance to the pocket, will not sag 35 or bulge outwardly when an article is placed in the pocket. In the case of the pockets now generally used on garments, there is a decided sagging of the edge adjacent the entrance to the pocket, and after the garment

is worn a short time this sagging is oftentimes 40 noticeable, even though there is nothing contained in the pocket. With my construction there is no sagging of the horizontal edge adjacent the entrance to the pocket at any time, and it will be clearly apparent 45 that in pressing a garment equipped with a pocket such as I have shown and described, the pressing operation will be a very simple matter, and the pocket can be pressed with the usual iron as easily as the ordinary pockets, particularly in view of the fact that the seam 17 will lie flush with the seam 18, when there are no articles in the pocket, and the inner face or integral flap 50 formed with the body of the garment, 55 will also lie flush with the body of the garment when there are no articles in the pocket.

It will be understood that various slight changes may be made from the construction 60 shown herein, without departing from the spirit of the invention, and that although my pocket is particularly adapted for use as a patch pocket on linen or other light summer suits, it may be used on all kinds of 65 material, and I do not limit myself to the particular form set forth, the scope of the invention being defined in the appended claim:

A garment having a slit therein conforming to the outline of the bottom and side edges of a pocket, which slit forms a pocket shaped flap that remains an integral part of the garment, a pocket shaped piece attached to the outer surface of the garment 70 to cover the opening produced by the formation of said flap, and a bellows piece attached along one edge to the edge of the flap and attached along its other edge to the pocket bounding edge of the garment. 75

In testimony whereof I affix my signature.

WILLIAM WEISS.
